GESELLSCHAFT, OF SIEMENSSTADT, NEAR BERLIN, GERMANY

TELEPHONE SYSTEM

Application filed February 13, 1931, Serial No. 515,478, and in Germany May 17, 1930.

The present invention relates to suppression of impulse series in telephone systems.

The object of the invention is to provide an arrangement for absorbing one or more impulse series in automatic telephone systems without the use of special relays. This is achieved in that the impulse transmitting relay remains energized by the switching devices associated with the repeater during the suppression of the impulse series.

An embodiment of the subject of the invention is shown in the drawing. The invention is not limited to this embodiment and only switching units necessary for the complete understanding of the subject of the invention have been shown.

Impulse series to a switch, e. g. a final selector (not shown) seized over line 11, are transmitted over the *a*— and *b*—leads of line 20 L, e. g. from the position of the exchange operator. When line L is seized by the plugging in the plus St into the jack K at the operator's position, the two windings of the differential relay A receive current in the following circuit: earth, contact 7c, winding I of relay A, lower left-hand coil of U2, *b*—lead, jack, plug, repeater U1, plug, jack *a*—lead, upper left-hand coil of U2, winding II of relay A, battery, earth. In this circuit relay A, the windings I and II of which are differentially connected, is not energized. The winding III of relay A is short-circuited over contact 12c. Relay A has thereby a slow acting deenergization and remains energized 35 while the contact 12c is closed during the impulse series. When the operator operates the contact *i*, which might belong to a dial, the winding I of relay A is short-circuited at the first closing of this contact, while winding II 40 of the relay is still connected to battery. Thereby relay A responds and closes its contacts 2a, 3a, and 4a. By the closing of contact 4a, relay R, constructed as a slow-acting relay, is energized. During the impulse transmission through contact *i* relay A, as described in the above, remains energized, and releases after the transmission of an impulse series due to the longer pause between the impulse series. At the energization of relay R contact 5r has also been

closed which prepared a circuit for relay C, constructed as a slow-acting relay. This circuit is only closed when, at the release of relay A, contact 3a is reclosed. The closing of contact 2a had no effect as contact 6c had not yet been closed. At the closing of contact 3a, due to the release of relay A, the following circuit for the relay C is completed, as relay R is constructed as a slow-acting relay and keeps its contact 5r closed during a short period after the opening of contact 4a; earth, contacts 5r and 3a, winding of relay C, jack, plug, battery, earth. Relay C, at its energization, operates its contacts 6c, 7c, and 12c. A locking circuit for relay C is closed over contact 6c on the line 11 leading in to the final selector, for the purpose of seizing the final selector and earthing the line, governed by the impulse contact 2a. When now the transmission of the second impulse series takes place, relay A is energized as described in the above. The contact 7c and 12c being opened, the slugging effect on relay A is removed and it therefore pulses. The opening and closing of contact 3a caused at the impulses of relay A, have no effect as relay C remains energized over its contacts 6c. By the opening and closing of contact 2a the succeeding impulse series are transmitted over line 9 to the succeeding switch. Upon the setting up of the connection the conversation can take place over the repeaters U1 and U2, the plug and jack. After the end of the conversation, the original condition is reinstated by the pulling out of the plug St.

In this manner it is achieved that the first impulse series is suppressed. A plurality of impulse series can also be suppressed in this manner by the provision of simple auxiliary means and instead of the short circuiting of one of the windings of relay A, a locking winding could further be provided, which maintains the impulse relay energized while the impulse winding itself is actuated, or a differential winding can be provided which has the described effect.

What is claimed is:

1. In a repeater, an incoming and an outgoing line, an impulsing relay, means for 100

transmitting digit impulses over said incoming line to control said relay, means controlled by said relay for repeating said impulses over said outgoing line, and a normally short-circuited winding on said relay for maintaining said relay energized throughout the first series of impulses.

5. In a repeater, an incoming and an outgoing line, an impulsive relay controlled by digit impulses received over said incoming line, means controlled by said relay for repeating said impulses over said outgoing line, a normally short circuited winding on said relay for rendering the same slow-acting so that it remains energized throughout the first series of impulses, and means for opening said short-circuit at the end of said first series of impulses.

6. In a repeater, an incoming and an outgoing line, a line relay responsive to impulses received over said incoming line and adapted to repeat the impulses over said outgoing line, and means for maintaining said relay energized during the first series of impulses so that said series is not repeated over said outgoing line.

7. In a repeater, an incoming and an outgoing line, a line relay responsive to impulses received over said incoming line and adapted to repeat the impulses over said outgoing line, means for maintaining said relay energized during the first series of impulses so that said series is not repeated over said outgoing line, and means responsive to the termination of said series of impulses for disabling said first means.

8. In a telephone system, an impulsive relay responsive to digit impulses, a second relay operated responsive to the first operation of said impulsive relay, a third relay, contacts on said second relay for preparing a circuit for said third relay, a normally short-circuited winding on said impulsive relay for maintaining the same energized throughout the first series of impulses, contacts on said impulsive relay for completing the circuit of said third relay when the impulsive relay deenergizes at the end of said series of impulses, and contacts on said third relay for opening the short-circuit around said winding.

9. In a telephone system, an impulsive relay responsive to digit impulses, a normally short-circuited winding on said relay for maintaining said relay operated during the first series of impulses, a second relay, means for energizing said second relay at the termination of said series of impulses, and contacts on said second relay for opening said short-circuit.

10. In a telephone system, a line relay, means for transmitting a plurality of series of impulses to said relay, means controlled by said relay for repeating said impulses, and means for absorbing one of said series of im-

pulses, said last means including a short-circuited winding on said relay which renders the relay slow to release so that it does not respond to the impulses of said series.

11. In a telephone system, a line relay, means for transmitting a plurality of series of impulses to said relay, means controlled by said relay for repeating said impulses, and means for absorbing one of said series of impulses, said last means including means for rendering said relay inoperative to respond to the impulses of said series.

12. In a telephone system, a line relay, means for transmitting a plurality of series of impulses to said relay, an outgoing impulsive circuit, means controlled by said relay for repeating said impulses over said outgoing impulsive circuit, means including a short-circuited winding on said relay for absorbing one of said series of impulses, and means effective at the termination of said series for opening the short-circuit of said winding and for preparing said outgoing impulsive circuit.

13. In witness whereof, I hereunto subscribe my name this 13th day of January, A. D. 1931.

ALFONS PEISSNER.
